UNITED STATES PATENT OFFICE.

THOMAS K. REA, OF CHARLOTTE, NORTH CAROLINA.

LEASE COMB AND REED.

1,390,162.

Patented Sept. 6, 1921.

Application filed April 5, 1921. Serial No. 458,798.

To all whom it may concern:

Be it known that I, THOMAS KIRKPATRICK REA, a citizen of the United States, residing at Charlotte, in the county of Mecklenburg and State of North Carolina, have invented certain new and useful Improvements in Lease Combs and Reeds; and I do hereby declare the following to be a full, clear, and exact description of the invention, such as will enable others skilled in the art to which it appertains to make and use the same.

My invention relates to improvements in lease combs and reeds for use on warping machines in preparing the yarn prior to its being dyed and prepared for the loom.

According to the prior practice it has been customary to use lease combs in which the yarns are conveyed in pairs, and there is a tendency of the two threads thus conveyed to twist together as the threads are being conveyed through the combs on the warping machine. This causes the threads thus twisted to stick together. Especially is this true when the yarn is formed into hanks and dyed, and when the yarn is further conveyed to the beamer to be prepared for the loom. The beamer, when beaming the yarn, is frequently compelled to stop his machine for the purpose of separating the twisted threads, and a thread thus twisted frequently breaks, causing further unnecessary delay and labor on the part of the beamer while tying the broken threads.

Furthermore, when the yarn (also known as the warp) is conveyed to the loom the beamer knots cause the weaver serious trouble, frequently resulting in the preparation of defective cloth and retarding the production.

My invention obviates the defects just mentioned, as my lease comb conveys each thread separately, with the threads at a uniform distance from each other, thus preventing a tendency of the threads to twist together and to stick when dyed, thereby saving considerable time and expense while the yarn is being conveyed through the beaming machine.

As a further result the weaver will not be delayed by the troublesome beamer knots. This will enable the weaver to produce a greater quantity of cloth per loom and run a greater number of looms, and to produce a better grade of cloth.

My invention will be more fully understood after reference to the accompanying

drawings, in which like parts are indicated by similar reference symbols throughout the several views, and in which:

Figure 1 is a front elevation of a lease 60 comb constructed according to my invention.

Fig. 2 is an end view of the comb shown in Fig. 1, as seen from the left of said figure.

Fig. 3 shows a section along the line 3—3 of Fig. 1, and looking in the direction of the 65 arrows.

Fig. 4 is a detail view showing on a larger scale one of the dents provided with the guide lips which form a groove for the oppositely disposed hook.

Fig. 5 shows a section along the line 5—5 of Fig. 4, and looking in the direction of the arrows.

Fig. 6 shows a section along the line 6—6 of Fig. 3, on a larger scale, and shows one 75 of the thread supporting hooks which is stamped out of the corresponding dent.

Fig. 7 shows a lease reed constructed according to my invention, in which the various dents are provided, respectively, with 80 two sets of lips to form grooves for the corresponding two sets of hooks provided in the opposite dent.

Fig. 8 shows a section along the line 8—8 of Fig. 7, and looking in the direction of the 85 arrows.

Fig. 9 shows a section along the line 9—9 of Fig. 7, and looking in the direction of the arrows.

Fig. 10 shows the reverse side of the central portion of Fig. 8, but on a larger scale; and

Fig. 11 shows a section along the line 11—11 of Fig. 9, and looking in the direction of the arrows.

Referring first to Figs. 1 to 6, the lease comb comprises a series of dents A and B which are adjustably spaced apart in the usual way, by means of the expansion springs C and D. The dents A are each 100 provided, preferably near their central portions, with laterally projecting lips a which are pressed out of the main body of the dent as shown most clearly in Figs. 1, 2 and

4. These lips form between the same a 105 groove a° into which projects the free end b° of the hook b. This hook is preferably stamped out of the dent B, as shown most clearly in Fig. 6.

The upper end b° of the hook b is turned 110 upward, and it will be seen that this point of the hook will be screened by the lips a,

with the result that the thread or yarn will be caught upon the neck b' of the hook, but will not engage the point of the hook. It will be seen that the curved lips will 5 guide the thread or yarn down to the smooth portion b' of the hook, and the yarn will be supported thereon against dropping downward between the adjacent dents, but at the same time will slide freely between the said 10 dents. By this co-acting arrangement of the lips and hooks the spaces between each pair of dents are left entirely clear as shown at E in Fig. 1, with the result that of each pair of yarns which pass through the comb 15 one yarn is supported on the corresponding hook and lips, and the adjacent yarn is free to be moved upward or downward in the passageway E; and that there is no possibility of the yarn, which I will indicate by 20 F, seen to the left of Fig. 1, coming into contact with or fouling the yarn, which I have marked F' in said figure.

While I have referred to two only of said 25 yarns, it will be obvious that the operation of all of the yarns in pairs will be the same as of the single pair of yarns just referred to.

Referring now to the double comb structure, or properly speaking, the reed structure shown in Figs. 7 to 11, the dents A' 30 and B' are provided, respectively, with double sets of lips a and double sets of hooks b , the parts being merely duplicated instead of arranged singly as in the former figures.

The dents A' and B' of this construction 35 may be either assembled in permanent fixed relation, as shown in Fig. 7, or they may be provided at the top and bottom with a suitable expansion spring arrangement similar to that shown in Fig. 1, already described, 40 and well known in the art.

In the construction shown in Figs. 7 to 9, the dents are secured in a frame comprising the transverse pieces G and G' and the vertical members I and I', but as previously 45 stated suitable expansion springs may be used in this frame if desired.

In the operation of the lease combs shown in Figs. 1 to 6, the yarns are fed into the spaces between the dents from the open 50 tops of the comb; while in the construction shown in Figs. 7 to 11 the yarns F² and F³ are drawn through the spaces between the dents, there being one yarn between each pair of dents.

55 In the reed arrangement shown in Fig. 7, the yarns F² are limited in their vertical travel by the oppositely disposed hooks b , while the yarns F³ are free to travel up and down in the corresponding slots E' between 60 the pairs of dents.

In the construction shown in Fig. 1, a comb is provided which is adapted for use with the well known machines in which lease combs now well known in the art are employed, and it is a part of my invention 65

that the use of my improved lease comb shall not in any way require any change in the construction of the machines which are now well known in the art.

In a similar way with the reed arrangement shown in Fig. 7, I purpose to use this with well known types of machines which are now generally in use in the art, without necessitating any change whatever in the construction of the machine *per se*, the 70 reeds being applied and removed in the same way as are the reeds now generally in use for accomplishing a similar purpose.

It will be noted that by the inter-penetrating hook and lip arrangement herein 75 described and shown, the adjacent dents may be spaced farther apart, or moved closer together without in any way impairing the feature requisite in such devices of preventing the yarn from passing beyond a given 80 point in the comb or reed.

In the prior art instead of the lip and 85 interpenetrating hook and groove arrangement shown herein, permanent lugs are provided which space the dents apart at a pre- 90 determined distance and do not permit of these spacing adjustments just referred to.

Thus it will be seen that with my herein 95 described invention all the dents of the comb or reed may be spread apart or drawn together simultaneously to conform to varying sizes of yarn and to various widths of the warp. Thus all the spaces between the dents may be spaced equidistant, and close together, or far apart within the limits desired. 100

It will be noted that the comb or reed may be made of any desired width, and that the dimensions of the various parts may be changed from those shown, without in any way affecting the essence of my invention. 105

It will be obvious that various modifications might be made in the herein described apparatus, and in the construction, combination and arrangement of parts which could be used without departing from the 110 spirit of my invention; and I do not mean to limit the invention to such claims except as particularly pointed out in the claims.

Having thus described my invention what I claim and desire to secure by Letters Patent of the United States is:—

1. In a lease comb or reed, the combination with a series of dents formed of resilient metal strips each having their opposite sides bent inward intermediate of their length to form a groove with rounded lips on either side thereof, of a second series of dents each provided with a prong adapted to project into the groove of the opposite dent, the said first and second series of dents being grouped in pairs with an unobstructed passage for the yarn between each of said pairs on the reverse side of the dents from said tongues and lips, respectively. 120

2. In a lease comb or reed, the combination 125

- tion with a series of dents formed of resili-
ent metal strips each having their opposite
sides bent inward intermediate of their
length to form a groove with rounded lips
5 on either side thereof, of a second series of
dents each provided with a laterally pro-
jecting hook stamped out of the body por-
tion thereof, adapted to project into the
groove of the opposite dent, the said first
10 and second series of dents being grouped in
pairs with an unobstructed passage for the
yarn between each of said pairs on the re-
verse side of the dents from said tongues
and lips, respectively.
- 15 3. In a lease comb or reed, the combina-
tion with a series of dents formed of resili-
ent metal strips each having their opposite
sides bent inward intermediate of their
length to form a groove with rounded lips
20 on either side thereof, of a second series of
dents each provided with a prong adapted
to project into the groove of the opposite
dent, the said first and second series of dents
being grouped in pairs with an unobstructed
25 passage for the yarn between each of said
- pairs on the reverse side of the dents from
said tongues and lips, respectively, with
means for simultaneously moving all of said
dents toward or away from each other, for
varying the spacing between same when de-
sired. 30
4. In a lease comb or reed, the combina-
tion with a series of dents formed of resili-
ent metal strips each having their opposite
sides bent inward intermediate of their
length to form a groove with rounded lips
35 on either side thereof, of a second series of
dents each provided with a laterally pro-
jecting hook stamped out of the body por-
tion thereof, adapted to project into the
groove of the opposite dent, the said first
40 and second series of dents being grouped in
pairs with an unobstructed passage for the
yarn between each of said pairs on the re-
verse side of the dents from said tongues
and lips, respectively, with means for simul-
taneously moving all of said dents toward
45 or away from each other, for varying the
spacing between same when desired.

THOMAS K. REA.
